UNITED STATES PATENT OFFICE.

JOEL U. ADAMS, OF CINCINNATI, OHIO.

HERNIAL TRUSS.

SPECIFICATION forming part of Letters Patent No. 737,051, dated August 25, 1903.

Application filed February 18, 1901. Serial No. 47,817. (No model.)

To all whom it may concern:

Be it known that I, JOEL U. ADAMS, a citizen of the United States, and a resident of the city of Cincinnati, in the county of Hamilton and State of Ohio, have invented certain new and useful Improvements in Trusses, of which the following is a specification.

The several features of my invention and the various advantages resulting from their use conjointly or otherwise will be apparent from the following description and claims.

In the accompanying drawings, making part of this application, and in which similar letters of reference indicate corresponding parts, Figure 1 is a front view in perspective of a truss, illustrating my improvements. Fig. 2 is a similar view, but showing the billet-strap in part disconnected and the perineal strap disengaged and by dotted lines showing the capacity of the pad for change of position in adjustment. Fig. 3 represents a transverse central section of the pad and its accompanying parts as I construct them. This figure also shows a transverse section of the belt where it is embraced between the pad and its securing-piece.

I will now proceed to describe my invention in detail.

A indicates a belt. The portion B of this belt consists of a thin spring B², usually made of metal incased in a leather or other good covering B³. The portion C of this belt consists of a flexible piece, usually of webbing. This may or may not be elastic in the direction of its length. The free end of this portion C is provided with an end piece D, known as a "tongue."

The parts already described were all old and well known previous to my invention.

Upon the truss and preferably upon the portion B, near its free end, I locate a staple E, whose ends E² E³ are respectively secured to the truss. The space E³ of the staple admits the tongue. The pad H proper may be of any desired construction, and it may be a hard or a soft pad, as desired. To the back of this pad I affix a broad piece K of stiff strong material, preferably metal. One end K² of this piece K is connected to one portion of the pad by a set-screw M and the other end K³ of this piece K is connected to the pad by a set-screw N. The portion B of the truss passes

between the pad H proper and this piece K, and this piece is long enough so that the portion B may pass beneath the piece K and over the pad when the length of piece K makes quite an oblique angle to the length of portion B. By such a lengthening I am enabled to vary the angle which this piece and the pad make with portion B by loosening the set-screws M and N and then changing the position of the pad. I am thus enabled to adapt the angle and position of the pad to the need of the patient—that is, to the proper retention and pressure upon the part afflicted with hernia. Thus in Fig. 65 2 I indicate by solid lines one position which the pad may be caused to take and in dotted lines another position which the pad may be made to assume. The pad may be placed in many intermediate positions, as necessity dictates. When such trusses are employed, the perineal strap P is with scarcely an exception employed. The construction of this strap may be varied. When present, I provide means for its retention. A well-known mode of connecting it at rear to the belt is shown in Figs. 1 and 2. At the front I provide the following means for its attachment—namely, I form the set-screw with an extension M² between an annular flange M³ and its free enlarged end M⁴. Over this extension the opening S of the part P² of the perineal strap P is placed. The pressure on this strap draws it down and draws the part P² down, and the extension M² enters the slot S² and is locked therein. To disengage the part S² from the extension M², the operation is reversed.

The mode of connection of the perineal strap at the front is very simple, economical, and convenient. At the center of the piece K, I erect a stud T, having a contracted neck T². This stud is to be received into the desired hole D² of the tongue D.

The mode in which my invention operates is in general as follows: The pad is moved to the proper place on the belt and set at the correct angle to accomplish the object for which it is present. The set-screws M and N are now tightened and the belt tightly clamped between piece K and the pad H. The truss is duly located in position upon the body of the person who is to wear it. The tongue is then drawn forward over the belt and beneath the staple E and after being drawn taut is

fastened over and on the stud T. The front end of the perineal strap is brought forward and up and duly connected, as prescribed, to the screw M. The operation is now completed.

It will be observed that the adjustable piece K, in connection with its screws M and N and with the stud T, has, first, a capacity for longitudinal adjustment along the belt; secondly, a capacity for any desirable angulated position relative to the belt; thirdly, furnishes means for the attachment of the perineal strap at front and of the tongue of the belt. Nor is this all. By withdrawing the screws M and N the pad can be removed from the belt and reattached thereto in a reversed position. Such change is the work of but a few minutes. The truss has thus been reversed. Thus this feature of my improvement renders the truss being capable of use for hernia in the right or left inguinal region, as necessary. That my invention is also simple and economical is obvious.

What I claim as new and of my invention, and desire to secure by Letters Patent, is—

1. In a truss, a pad, a belt, a clamping-piece extending across the belt on one side and in contact therewith, means for securing the

30 said clamping-piece at its ends directly to the pad to hold the back face of the pad in contact with the inner face of the belt, the said clamping-face being of a length to enable the pad to be shifted into different angular positions, said clamping-piece having a central stud, said belt having a tongue to engage the 35 central stud and a staple on the belt through which the tongue passes substantially as described.

2. In a truss, a pad, a belt, a clamping-piece extending across the belt on one side and in 40 contact therewith, means for securing the said clamping-piece at its ends directly to the pad to hold the back face of the pad in contact with the inner face of the belt, the said clamping-face being of a length to enable the 45 pad to be shifted into different angular positions, said clamping-piece having a central stud, said belt having a tongue to engage the central stud, a staple on the belt through which the tongue passes and a perineal strap 50 secured to the lower end of the clamping-piece, substantially as described.

JOEL U. ADAMS.
